[57] CLAIM

The ornamental design for a separable connector, substantially as shown.

DESCRIPTION

FIG. 1 is a perspective view of a separable connector showing my new design;
FIG. 2 is a top plan view thereof, the bottom being a mirror image;
FIG. 3 is an elevational view of the outer surface of the element shown to the rear of FIG. 1;
FIG. 4 is a top plan view of FIG. 3;
FIG. 5 is a bottom plan view of FIG. 3;
FIG. 6 is an elevational view of the side opposite that shown in FIG. 3;
FIG. 7 is an end elevational view taken from the left side of FIG. 3;
FIG. 8 is an end elevational view taken from the right of FIG. 3;
FIG. 9 is an elevational view of the outer surface of the forward element of FIG. 1;
FIG. 10 is a top plan view of FIG. 9;
FIG. 11 is a bottom plan view of FIG. 9;
FIG. 12 is an elevational view of the side opposite that shown in FIG. 9;
FIG. 13 is an end elevational view taken from the left of FIG. 9;
FIG. 14 is an end elevational view taken from the right of FIG. 9;
FIG. 15 is a perspective view similar to FIG. 1, but with the element to the rear of FIG. 1 rotated counterclockwise into view;
FIG. 16 is a perspective view of the opposite sides of the element of FIG. 15, further rotated apart.
